SCREW HOLDING ATTACHMENT FOR
SCREW DRIVERS

Robert J. Mahaffey, Texarkana, Tex.

Application February 18, 1949, Serial No. 77,198

1 Claim. (Cl. 145—52)

1

The present invention relates to automatic screw holding screwdriver and it consists in the combinations, constructions and arrangements of parts herein described and claimed.

It is an object of the present invention to provide a screwdriver of conventional character having a simple attachment therefor which provides means for holding a screw thereon.

Another object of the invention is the provision of a device of the character set forth having means for automatically grasping and retaining a screw when the same is removed by a screwdriver utilizing the present invention.

Another object of the invention is the provision of simple and effective means for attaching a screw holder to a screwdriver.

Other and further objects of the invention will become apparent from a reading of the following specification taken in conjunction with the drawing, in which:

Figure 1 is a side elevational view of an embodiment of the invention.

Figure 2 is a fragmentary elevational view, partly in section, showing the device in engagement with a fully embedded screw.

Figure 3 is a view similar to Figure 2 showing the device in engagement with a screw which is only partially engaged in a wall or the like.

Figure 4 is an enlarged sectional view taken along line 4—4 of Figure 1.

Figure 5 is an enlarged sectional view taken along line 5—5 of Figure 1, and

Figure 6 is a fragmentary perspective view of a blank of material utilized in the invention.

Generally there is provided an attachment for a conventional screwdriver which is formed of a single blank of material adapted to be bent into substantially cylindrical shape and which engages over a washer which is pressed into position upon the shank of a screwdriver. The cylindrical member is provided with a plurality of fingers which are adapted to engage the head of a screw and the cylindrical member is reciprocally movable upon the screwdriver and is urged toward the blade by means of a coil spring bearing against the washer and a series of inwardly directed detents formed integrally with the cylindrical member. The device is particularly useful in securing and retaining a screw upon the blade of a screwdriver when a screw is removed from an imbedded position. The cylindrical member referred to is formed of spring metal thereby providing resilience for the screw head-engaging fingers.

2

Referring more particularly to the drawing, there is shown therein a screwdriver having a handle 10, a shank 11 and a blade 12. At a point adjacent the blade end of the shank 11 a washer 13 is preferably pressed into position upon the shank 11 although the same may be shrunken, welded or otherwise affixed to the shank.

A blank of flat spring metal is formed with a body 14 and a series of screw engaging fingers 15. 10 The blank is rolled or bent into a substantially cylindrical formation to encompass the washer 13 in such manner that the fingers 15 extend outwardly to completely surround the blade 12. The fingers are then bent inwardly, as indicated at 15 16, to provide a better grip for engaging a screw 17.

At the point of juncture between the fingers 15 and the body 14 a series of detents 18 are bent inwardly to provide one abutment for a coil spring 19 which surrounds the shank 11 and which has its other end in contact with the washer 13. The inner end of the body 14 is provided with a series of inwardly extending integrally formed detents 20 which engage with the washer 13 when the body 14 is extended to its outermost position.

In operation, it will be apparent that when it is desired to insert a screw into, for example a board 21 or the like, it is only necessary to place the screw 17 in contact with the blade 12 in the 20 conventional manner, the fingers 15 yielding during this operation and encompassing the screw 25 when the screw has been seated with the blade 12. Thereafter the screw may be fully engaged with the board 21 by turning the handle 11 in the customary manner, the portion 16 of the fingers 15 automatically moving outwardly of the screw head when they engage with the wall 21 and are forced outwardly by the head of the screw against their inherent springiness. When 30 it is desired to remove a completely embedded screw, the screwdriver is again used in the conventional manner and as soon as the handle 10 and consequently the shank and blade 11 and 35 12 are turned a sufficient number of times the head will protrude from the surface of the board and the fingers 15 will cause the portions 16 thereof to engage the head of the screw to automatically retain the same in contact with the blade 12 without any outside intervention such as, for example, the use of the operator's fingers. It will be seen that the spring 19 acts to retain the fingers 15 in a forward position, that is to say in a position where the fingers 15 and their inturned portions 16 fully encompass the blade 40 45 50 55 12. However, as a screw is forced into a board

21, for example, it will be seen that the entire cylindrical member including the body 14 and the fingers 15 will be moved inwardly of the shank 11 to allow the blade 12 to continue in contact with the head of the screw as will be more clearly illustrated in Figure 2 of the drawing.

While but one form of the invention has been shown and described herein, it will be readily apparent to those skilled in the art that many minor modifications of the invention may be made without departing from the spirit of the invention or the scope of the appended claim.

What is claimed is:

A device of the character described comprising, in combination, a screwdriver having a handle, a shank and a blade, a collar affixed to the shank adjacent the blade, a cylindrical body surrounding the shank and collar, a series of spaced screw-gripping fingers formed integrally with the body and extending in the direction of the blade, a series of inwardly extending detents formed integrally with the body at the point of juncture between the body and fingers, each of said detents being positioned between a pair of adjacent fingers, a coil spring between the shank and the body and having one end abutting the detents

and its other end abutting the collar, and a series of inwardly directed detents formed integrally with the body at its free end and positioned between the handle and the collar, said cylindrical body, both series of detents and fingers all being formed of a single piece of flat spring metal.

ROBERT J. MAHAFFEY.
